UNITED STATES PATENT OFFICE

GARTH G. GILPIN, OF RIVERSIDE, ILLINOIS, ASSIGNOR TO UNION METAL PRODUCTS COMPANY, OF CHICAGO, ILLINOIS, A CORPORATION OF DELAWARE

HINGED SHANK COUPLER

Application filed February 2, 1928. Serial No. 251,360.

The device relates to attachments of a car coupler to the draft gear or shock absorber of a railway car and comprises a coupler having a shank consisting of two pieces pivoted and interlocked together to accomplish certain desired objects. The device might also be described as a coupler having a spreader hinged and interlocked therewith.

The object of the invention is to increase the life of the coupler by decreasing the wear and mashing of the rear end of the shank where it engages the draft gear follower or casing.

Another object of the invention is to increase the life of the coupler by increasing the bearing area between the draft key and the coupler.

Another object of the invention is to provide means so that the car coupler will have a surface contact with the draft gear casing (or follower) in any lateral position it may assume in service.

Another object of the invention is to provide means so that the car coupler will have a surface contact with the front draft key in any lateral position it may assume in service.

Another object of the invention is to provide a spreader connected to the coupler shank so as to provide arcuate buffering (compression) and pulling (tension) surfaces therebetween.

Another object is to provide an arrangement for locking the spreader to the coupler and forming them so they can be assembled only by certain movements, which movements they can not make while in assembled position with associated parts of the car.

Another object is to attach the spreader to the coupler without any hinge or fulcrum pin, and in fact without any split key, cotter, nut or similar securing means.

Another object is to provide a spreader which prevents the portions of a bifurcated coupler shank from spreading or coming together when the coupler is under compression or tension.

Another object is to provide a spreader which is reversible and cannot be improperly applied to the coupler.

In the drawings:

Fig. 1 shows the coupler, spreader, draft

gear and associated parts of the car when the draft gear is in compressed position and the coupler head is swung laterally.

Fig. 2 is similar to Fig. 1 but shows the coupler pulled outwardly.

Fig. 3 shows the relation of the coupler shank and the spreader in normal position.

Fig. 4 is a side elevation of Fig. 3.

Fig. 5 shows the spreader partially assembled with the coupler shank.

Fig. 6 is a perspective view of the rear end of the coupler shank.

Fig. 7 is a perspective view of the spreader.

Fig. 8 is a perspective view of the filler block.

The usual parts of the car are shown, such as coupler head 1; coupler shank 2; draft gear 3; draft sill 4; front draft key 5; rear draft key 6; yoke 7; striking casting 8 and rear draft gear stop 9.

In the ordinary construction the buff on the coupler is transmitted to the draft gear casing 10 (or follower) by the coupler shank 2 and the pulling force on the coupler is transmitted to the draft gear through the draft keys and yoke.

If the present standard coupler is swung laterally under compression there is only a line contact between the coupler shank and the draft gear casing. This, experience has shown, causes considerable mashing and wear of both corners of the coupler and then the middle of the coupler shank is mashed and worn, which causes a foreshortening of the coupler.

When the present standard coupler is pulling the car there is only a line contact between the coupler and front draft key, which causes an elongation of the key slot resulting in excessive lost motion in the draft gear arrangement.

These two defects are responsible for the scrapping of a great many couplers.

In the preferred form the coupler is provided with oppositely projecting vertically disposed pintles 20 upon which a filler or wearing piece 21 is pivoted. This block is preferably made of softer material than either the coupler or the spreader so that the friction of the moving parts will wear it in-

stead of the spreader, which block is easily removed and replaced. The coupler has curved or arcuate rear ends 24 concentric with the pivot or pintle 20 which form buffing surfaces. The coupler is also provided with a rib 40 having buffing surfaces 25 concentric with the pivots 20 which are positioned in front of the pivot so that the pivot is between the two arcuate buffing surfaces 24 and 25. The spreader has spaced apart horizontal flanges 30-31 connected by a main wall 32 having a flat bearing surface 33 for engagement with the draft gear casing or follower and each flange is provided with a vertically disposed rib 34 having an arcuate front surface 35 for sliding engagement with the arcuate surface 25 on rib 40 of the coupler. Arcuate faces 37 are provided on the front of the spreader wall which slidably engage the arcuate rear end 24 (or ends) of the coupler. The filler 21 has an aperture 26 for engagement with the pintle 20 and is of rectangular shape and in fact is preferably square to eliminate the possibility of improper application. In service the front part 22 of the filler is a pulling surface and engages the surface 36 of the rib 34 on the spreader and prevents the filler 21 from rotating around the pintle 20; i. e., retains the filler in operative position. The rear surface 23 of the filler is a buffing surface and engages the straight portions 39 on the front of the wall 32 of the spreader.

A straight bearing surface 38 is provided on the front wall of the spreader for engagement with the front draft key 5. This bearing surface is made longer than the width of the coupler shank and in fact is made as long as is permitted by the space between the arms of the yoke (see Fig. 3) so as to reduce the wear on the key and eliminate the elongation of the keyway.

In the operation of my device the compression or buff exerted on the coupler is transmitted by the pivots 20 to the buffing surface 23 on the fillers 21 and the arcuate buffing surface 24 on the rear end of the coupler to the arcuate surfaces 37 on the wall of the spreader and thence to the draft gear casing 10. Part of the compression is transmitted to the ribs 34 of the spreader by the arcuate rib 40 on the coupler.

The spreader is made wider than the coupler shank, in fact, is made as wide as possible between the portions of the yoke so as to furnish a large bearing area between it and the draft gear casing. (See Fig. 3.)

The pulling force exerted on the coupler is transmitted to the spreader through pivots 20 and the pulling surface 22 on the fillers and thence to the draft gear through the front draft key and the yoke.

In my arrangement, therefore, there is a surface contact (in contrast with a line contact) between the spreader and draft gear

casing or follower and between the coupler and spreader in any lateral swung position the coupler may assume in service when the coupler is under either compression or tension, and, furthermore, there is always a surface contact between the coupler and front draft key when the coupler is pulling the car, no matter what lateral position it may be in.

The coupler now in general use is provided with a slot to accommodate the forward draft key 5 and the size and location of this slot and key are prescribed by the A. R. A., therefore, for interchangeability I prefer to comply with these standards, thus the keyway bifurcates or splits the rear end of the coupler. (See Fig. 6.) The spreader is also provided with a spacer 52 projecting into the slot 53 so that when the coupler is under compression, this spacer prevents the spaced apart portions 54-55 of the bifurcated coupler from coming together, and furthermore the flanges 30-31 of the spreader prevent the portions of the split coupler from spreading apart. The flanges of the spreader may be provided with lateral lips 41 which underlie the projections 42 to prevent the flanges from spreading apart which they may have a tendency to do when the coupler is under compression. This arrangement also prevents the bifurcated portions of the coupler and the flanges of the spreader from spreading apart when the coupler is under tension. Besides its other functions, therefore, the spreader prevents distortion of the bifurcated coupler shank.

The spreader is assembled with the coupler by engaging the fillers with the pivots and inserting the coupler shank in the spreader until the pivot point of the concentric arcuate surfaces on the pintle coincides with the pivot point of the arcuate surfaces on the spreader and then rotating or swinging the spreader substantially ninety degrees. When the parts are assembled (see Fig. 3) and the yoke 7 and key 5 are in place it is impossible for the spreader to become disengaged from the coupler or even to become cocked or assume a binding position. While the parts are in operative position it is impossible for the fillers to be accidentally or intentionally removed.

This interlocking arrangement eliminates the necessity of a hinge pin which is very undesirable because it is broken in service and frequently falls out of position, thus causing the device to become inoperative and resulting in serious damage to the car. I have also eliminated the use of any nut or split key or similar retaining means for any part of my device. Experience has shown that such devices are frequently inadvertently or otherwise omitted by the workmen and are sometimes loosely applied so that the jolting of the car in service jars them entirely out of place.

The spreader is made symmetrical about its middle horizontal plane so that it may be applied either way; or in other words, is reversible and furthermore is foolproof in that

5 it can not be improperly applied.

I have used the term draft gear casing to indicate the box or housing which usually encases the shock absorbing mechanism. The projection 57 maintains the proper relation

10 between the coupler and draft gear.

The accompanying drawings illustrate the preferred form of the invention, though it is to be understood that the invention is not limited to the exact details of construction

15 shown and described, as it is obvious that various modifications thereof within the scope of the claims will occur to persons skilled in the art.

This application discloses and claims an

20 improvement upon the invention for "coupler with hinged shank" filed by Arthur E. Small on February 2, 1928, Serial No. 251,330.

I claim:

1. In a railway car structure, a car coupler

25 provided with oppositely projecting pintles and with its rear end arcuated to form a curved buffing surface concentric with said pintles, a filler pivotally surrounding each pintle having a straight rear buffing surface, and a spreader mounted upon both fillers having a main wall with arcuate buffing surfaces slidably engaging the arcuate end of the coupler and straight portions engaging the straight buffing surfaces of the fillers.

35 2. In a railway car structure, a car coupler provided with oppositely projecting pintles and with its rear end arcuated to form a curved buffing surface concentric with said pintles, a filler pivotally surrounding each

40 pintle having a straight rear buffing surface and a straight front pulling surface, and a spreader mounted upon both fillers having a main wall with arcuate buffing surfaces slidably engaging the arcuate end of the coupler

45 and straight portions engaging the straight buffing surface of the filler and a straight pulling surface engaging the straight pulling surface of the filler.

3. In a railway car structure, a car coupler

50 having oppositely projecting pintles, a filler pivotally surrounding each pintle and a spreader having a main wall with opposite flanges overlying said pintles, each of said flanges provided with a vertically disposed

55 rib which engages one of said fillers and retains it in operative position.

GARTH G. GILPIN.
